[57] CLAIM

The ornamental design for a liquid applicator, as shown and described.

DESCRIPTION

FIG. 1 is a top perspective view of a liquid applicator showing my new design;

FIG. 2 is a side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a top perspective view of a second embodiment of the design shown in FIG. 1;

FIG. 8 is a reduced side elevational view thereof;

FIG. 9 is a front elevational view thereof;

FIG. 10 is a rear elevational view thereof;

FIG. 11 is a top plan view thereof;

FIG. 12 is a bottom plan view thereof;

FIG. 13 is a top perspective view of a third embodiment of the design shown in FIG. 1;

FIG. 14 is a reduced side elevational view thereof, the opposite side being a mirror image;

FIG. 15 is a front elevational view thereof;

FIG. 16 is a rear elevational view thereof;

FIG. 17 is a top plan view thereof;

FIG. 18 is a bottom plan view thereof;

FIG. 19 is a top perspective view of a fourth embodiment of the design shown in FIG. 1 wherein the only differences reside in the configuration of the supporting arm and the shape of the opening on top of the supporting arm; and

FIG. 20 is a front elevational view of a fifth embodiment of the design shown in FIG. 1 wherein the only difference resides in the appearance of the applicator wheel plate, the supporting arm being partially shown for ease of illustration only.

The broken line showing of a bottle in FIG. 1 is for illustrative purposes only and forms no part of the claimed design.
